UNITED STATES PATENT OFFICE.

HENRY J. VIGNEAULT, OF WORCESTER, MASSACHUSETTS, ASSIGNOR OF ONE-HALF
TO GEORGE N. VIGNEAULT, OF WORCESTER, MASSACHUSETTS.

FRONT FASTENING FOR SOFT COLLARS.

1,425,153.

Specification of Letters Patent. Patented Aug. 8, 1922.

Application filed March 29, 1921. Serial No. 456,527.

To all whom it may concern:

Be it known that I, HENRY J. VIGNEAULT, a citizen of the United States, residing at Worcester, in the county of Worcester and 5 State of Massachusetts, have invented a new and useful Front Fastening for Soft Collars, of which the following is a specification.

This invention relates to an improved device for use on a soft collar for holding 10 down the front of the collar. The principal objects thereof are to provide a device which will do away with the use of a detachable pin or the like for that purpose; permit of fastening the device at the center instead of 15 at the side; and also, in its preferred form, eliminate the buttons which are often used for attaching such parts. Further objects and advantages of the invention will appear hereinafter.

Reference is to be had to the accompanying drawings in which—

Fig. 1 is a front view, in perspective, of a soft collar embodying a preferred form of this invention;

Fig. 2 is an enlarged view of the connecting device;

Fig. 3 is a plan of the same with parts in section;

Fig. 4 is a sectional view on the line 4—4 of Fig. 2;

Fig. 5 is a view similar to Fig. 1 showing a modification;

Fig. 6 is a similar view showing it unfastened, and

Fig. 7 is a plan of the same.

It is customary to provide a link, pin or the like, very often detachable, to the front ends of a soft collar to hold these ends down and pass it under the tie. Such devices are 40 fastened or sometimes buttoned to the collar on the inside, in which case the fastening device or the buttons present difficulty in fastening and laundering the collar. The detachable pins that have been used injure 45 the collar and are likely to be misplaced and lost. They have also been of such construction as far as I am aware that it was necessary to fasten them under or through one edge of the collar.

This invention is designed to provide a construction in which the fastening takes place between the two front edges of the collar where the wearer can more conveniently get at it, and after being fastened is hidden 55 and which greatly improves the front of the

collar, and in its preferred form, does not involve any buttons or similar projections that are likely to interfere with the laundering of the collar, and which is permanently connected so that it can not be lost and contains nothing that will injure the collar or 60 leave any marks on the same.

In the form shown in the first four figures, the invention involves two pieces of tape, strap or other material 10 sewed into 65 the edges opposite each other, and each reaching less than half way across the space between the front edges. These are located in the usual place and have the usual function, but instead of having a single one go 70 clear across and button under the edge as is usual, each one projects half way across and is provided with half of a separable fastening device at its free end. These two halves are connected together in any suitable way 75 and obviously require only simple manipulation.

In the form shown one of these fastening devices comprises a metal or other plate 11 having one or more perforations at the back 80 through which the tape 10 can be secured. This plate is thin and flat and preferably of spring material or material that will yield somewhat. It is provided with a longitudinal and preferably central slit 12 extending 85 in from the end, and this slit has an enlargement 13 about half way between its ends.

The companion piece consists of a plate 15 of similar character connected with the 90 tape in the same way and provided with two integral flanges 16 spaced from the plate far enough to receive the plate 11 between them. It is also provided with a projection 17 centrally located between these flanges for entering the slit in the other plate and finally 95 lodging in the enlargement 13 thereof.

These two elements of the connecting device are brought together and the flat one slid into the other between the flanges until 100 the projection enters the enlargement. Then they are held frictionally, but nevertheless with a sufficient degree of force to prevent disconnection of the parts by any ordinary strain to which it may be subjected. Nevertheless, a strong pull exerted on the two tapes will disconnect the two halves and leave them free. This constitutes a very simple and easily manipulated fastening device which is located centrally where the 110

wearer will not have to disarrange his collar or tie in order to attach the parts together and which is integral with the collar and consequently cannot be misplaced or lost. It furnishes no hindrance to the laundering or fastening of the collar and no buttons are necessitated for holding it.

Another form of the invention shown in Fig. 4 consists of a single loop 20 of elastic or non-elastic cord having both its ends secured between the layers of the collar in the same way that the tape is in the other form, and reaching about half way across. This is a permanent loop. On the other half there is a second loop 21 secured in the same way and somewhat longer. This has a free end which is intended to go through the loop 20 and then back under the collar and to fasten on a button 22 inside. This has not all the advantages above indicated, but it furnishes a simple and convenient way of connecting the two sides of the collar and does away with some of the troubles above indicated.

Although I have illustrated and described only two forms of the invention I am aware of the fact that further modifications can be made therein by any person skilled in the art without departing from the scope of the invention as expressed in the claims.

Therefore, I do not wish to be limited to all the details of construction herein shown and described, but what I do claim is:—

1. As an article of manufacture, a fastener for a soft collar or the like comprising two sheet metal plates, one having a longi-

tudinal slot enlarged at a distance from its end and the other having an integral projection for engaging in said enlargement, and integral side ears on one plate in position for guiding the other.

2. As an article of manufacture, a fastener for a soft fold collar or the like having two flexible pieces projecting from about the center of the front edge of the fold one on each side and each extending less than half way across the space between said edges, said fastening comprising two halves, one mounted on each flexible piece and each comprising a flat plate, one plate having a guide for the other, and said other plate having a projection slit centrally and longitudinally and adapted to engage in said guide to frictionally hold the parts together.

3. As an article of manufacture, a fastener for a soft collar or the like having two pieces of tape, each projecting from about the center of the front edge on each side and each one located horizontally and extending less than half way across the space between said edges, said two pieces of tape having at their ends the complementary halves of said fastening, one of said halves comprising a flat plate having a slot having an enlargement therein and the other half comprising a plate having a projection engaging in said enlargement to frictionally hold the parts together and one plate having a guide for the other.

In testimony whereof I have hereunto affixed my signature,

HENRY J. VIGNEAULT.
